[57] CLAIM

The ornamental design for a necktie, as shown and described.

DESCRIPTION

FIG. 1 is a front and right side perspective view of a necktie showing my new design in folded condition; FIG. 2 is a front elevational view thereof; FIG. 3 is a right side elevational view thereof, the left side being a mirror image thereof; FIG. 4 is a top plan view of the necktie in unfolded condition; FIG. 5 is a bottom plan view thereof; and FIG. 6 is a rear elevational view in the condition of FIGS. 1-3.
